UNITED STATES PATENT OFFICE.

GEORGES GROS, OF BORDEAUX, AND LOUIS GEORGE POURE, OF PARIS,
FRANCE.

APPARATUS FOR ATTACHING METALLIC SEALS.

SPECIFICATION forming part of Letters Patent No. 371,138, dated October 4, 1887.

Application filed May 4, 1887. Serial No. 237,037. (No model.) Patented in France January 26, 1887, No. 181,148, and in England June 28, 1887, No. 9,212.

To all whom it may concern:

Be it known that we, GEORGES GROS, of Bordeaux, France, and LOUIS GEORGE POURE, of Paris, France, have invented certain new and useful Improvements in Devices for Fastening Metallic Seals, (which has heretofore been patented to us by the Government of France, dated January 26, 1887, No. 181,148, and by the Government of England, dated June 28, 1887, No. 9,212,) of which the following is a specification.

In sealing letters heretofore use has been made of gum, sealing-wax, or wafers. These means are insufficient, as they do not furnish any security against reopening the letters, either by dissolving the gum or wafers by means of steam or by softening the sealing-wax by means of heat. Attempts have been made to produce a more perfect sealing of letters by means of metallic eyelets, which seal has been used in sending valuable letters by express. This, however, requires the punching of holes for the purpose of affixing the metallic eyelets; but even then the fastening is not absolutely safe, as the seal may be by means of pinchers removed from the eyelets, and after the envelope has been opened replaced again.

The object of this invention is to furnish an improved metallic seal and fastener for letters, by which the envelopes are absolutely closed and cannot be opened except by tearing the envelope.

The invention consists in the construction and combination of parts and details, as will be fully described and set forth hereinafter, and then pointed out in the claim.

In the accompanying drawings, Figure 1 represents a side elevation of our improved metallic seal. (Shown before application.) Fig. 2 is a side view of the same, showing it applied to an envelope. Fig. 3 is a side elevation, partly in section, of our improved device for applying the metallic seal. Fig. 4 is a plan of Fig. 3. Fig. 5 is a detail of the lower die drawn on a larger scale. Fig. 6 is a rear view of the envelope closed by our improved seals, and showing the device for applying the seal in dotted lines.

Similar letters of reference indicate corresponding parts.

Our improved metallic seal consists of a disk, *h*, of sheet metal, which is provided at its circumference with a number of pointed prongs, *p*, that are made integral therewith, and are about at right angles to the plane of the disk. 55 The prongs are forced through the paper, so as to bend up readily to the under side of the paper, as shown in the lower half of Fig. 2. The pointed ends of the prongs *P* are again bent upward and pierce the paper again, said 60 double-piercing securing the seal firmly and reliably in position and preventing any tampering with the envelope, as the envelope can only be opened by tearing it. The disk-shaped portion of the seal may be provided with initial 65 letters or other characters.

For applying the seal the apparatus shown in Figs. 3, 4, and 5 is used, which is composed of a base-plate consisting of a semicircular arm, *A*, which carries at one end a die, *M*, 70 having an annular depression or groove, *m*, as shown in Figs. 3 and 5. To a pivot, *K*, at the other end of the arm *A*, is applied a sleeve-shaped end of an oscillating arm, *B*, which carries at its opposite end, above the die *M*, 75 a cylindrical guide-tube, *c*, above which is mounted a button, *D*, said button being guided by a punch-shank, *d*, in the guide-tube *c*, and connected therewith by an annular spring portion, *s*, of rubber or other suitable material. 80

To the pivoted end of the arm *B* is applied a wire loop, *G*, by means of which the tube may be conveniently suspended. A spring, *r*, is attached to the pivoted end of the arm *D* and extended downwardly therefrom, as shown 85 in Fig. 3, said spring-arm bearing on the loop *G*, and thus holding the arm *B* in raised position. A heel, *n*, extends in upward direction from the sleeve end of the arm *B*, and serves for raising the arm *B* whenever a metallic seal 90 is to be inserted into the guide-tube *c*, the inner edge of the annular depression *m* of the die *M* imparting the double bending of the prongs of the seal, so that the prongs penetrate the paper at two points.

For applying the fastening metallic seal to the envelope the seal is first introduced into the guide-tube *c*. The left-hand edge, *o^x*, of the envelope is then moistened and closed before the right-hand edge of the envelope, *o^y*, is 100

moistened. The arm A is introduced through the unmoistened part of the envelope, so as to be placed below the sealed edges of the envelope to the point No. 3, where the seal has to be placed. The arm B is then quickly depressed by a blow upon the button D, which presses the prongs *p* through the paper and bends them against the under side of the paper and bends the points up into the paper, as shown in Fig. 2, by the action of the punch-shank *d* and the die *M*, the envelope before being moistened being provided with similar seals at the points 1 and 2, Fig. 6. To the center of the envelope is next applied the seal 5 in the same manner, and then the right-hand edge, *o'*, is moistened and another seal applied at 4.

With ungummed envelopes the fastening 2 can be applied without difficulty at any point of the envelope before applying any number of metallic seals. The fastening-tool may also be provided with a straight arm, as shown in dotted lines at A' in Fig. 4, in which case the arm is introduced through a slit, *g*, in the en-

velope, for sealing the same at any desired 25 point.

Having thus described our invention, we claim as new and desire to secure by Letters Patent—

The device for fastening seals herein described, composed of an arm having a die with an annular groove or depression at one end and an oscillating arm pivoted to the other end of the arm and provided with a guide-tube for the blank seals, and a spring button and shank 35 for clinching the prongs of the seal, substantially as set forth.

In testimony that we claim the foregoing as our invention we have signed our names in presence of two subscribing witnesses.

GEORGES GROS.
